UNITED STATES PATENT OFFICE.

HENRY W. ROSE, OF VICTORIA, TEXAS.

OIL RECLAIMER AND PURIFIER.

Application filed February 4, 1922. Serial No. 534,141.

To all whom it may concern:

Be it known that I, HENRY W. Rose, a citizen of the United States, residing at Victoria, in the county of Victoria and State 5 of Texas, have invented certain new and useful Improvements in Oil Reclaimers and Purifiers; and I do hereby declare the following to be a full, clear, and exact description of the invention, such as will enable

10 others skilled in the art to which it appertains to make and use the same.

The invention has relation to means whereby used lubricating oil may be reclaimed and the impurities eliminated therefrom so that the oil may be advantageously used for lubricating purposes, thereby producing a material saving and obviating the waste incident to discarding used lubricating oil charged with slush and other 20 impurities.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to 25 without departing from the nature of the invention.

The accompanying drawing illustrates a perspective view of an oil purifier embodying the invention, parts being broken away.

30 The purifier comprises a receptacle 1 which may be of any capacity and whose bottom is preferably made rounded. The receptacle, as shown, is mounted upon legs which are attached to the bottom 2, the legs 3 being of any height and construction. A drain cock 4 is connected centrally with the bottom 2 and provides means for drawing off impurities or for emptying the receptacle, as required. A sight gage 5 is provided at one side of the receptacle to indicate the level of the oil therein. A heating coil 6 is located within the receptacle 1 and may receive a heating medium from a suitable source. A steam pipe 7, leading from 35 a suitable source of supply, is connected with the inlet of the heating coil 6 and is provided in its length with a valve 8. A discharge pipe 9 connects with the outlet of the heating coil 6 and conveys the water of 40 condensation or spent steam to a suitable point of discharge. The discharge pipe 9

is provided in its length with a valve 10. A screen 11 rests upon the heating coil 6 and serves to retard the up-flow of the oil and to separate particles of impurities therefrom. A pipe 12 connects with the receptacle 1 a short distance above the level of the screen 11 and constitutes an outlet for the discharge of the oil after the impurities have been eliminated therefrom. 60

A funnel 13 occupies the upper portion of the receptacle 1 and is supported upon the upper edge thereof. A relatively large pipe 14 extends from the bottom of the funnel 13 to within a short distance of the bottom 2 of the receptacle and has a comparatively small opening 15 in its lower end for the discharge of the oil in the operation of the purifier. A screen 16 is disposed within the lower portion of the funnel 13 and serves to remove particles from the oil in the process of reclaiming the same. A cover 17 is fitted to the top of the funnel 13 to exclude dust and foreign matter. A plurality of valves 18 are provided at one side 70 of the receptacle 1 and are disposed at different elevations and are utilized to draw off the oil from the receptacle when cleaning the latter. 75

In the operation of the purifier, the funnel 13 is removed and a quantity of used oil is supplied to the receptacle 1 until the level corresponds approximately with the heating coil 6. The funnel 13 is now replaced and a quantity of the used oil is poured into the funnel to nearly or quite fill the same. The cover 17 is now placed in position and heat is applied to the coil 6 whereby to warm the oil adjacent or in contact with the coil. The heating of the oil renders the same more 80 fluid and facilitates the precipitation of impurities. The oil contained in the funnel 13 passes therefrom to the lower portion of the receptacle 1 and is slowly discharged therein from the relatively small opening 15 at the lower end of the pipe 14. The level of the oil in the receptacle 1 gradually rises until it reaches the overflow or discharge pipe 12 through which it passes and is delivered into a suitable vessel (not 85 shown) in condition to be again used for lubricating purposes, since all impurities, slush and the like have been eliminated. 90

It is observed that the heating coil 6 extends from the pipe 14 clear to the outer 100 wall of the receptacle 1 whereby to provide a maximum extent of heating surface. A 110

thermometer 19 is attached to a side of the receptacle 1 a short distance below the level of the heating coil 6 to indicate the temperature of the contents of the receptacle, there-
5 by providing for regulating the same as may be required.

A rod 20 extends through the funnel 13, pipe 14 and cover 17 and is provided at its upper end with an eye or finger piece 21.
10 The lower end of the rod 20 extends through the opening 15 in the lower end of the pipe 14 and is provided with a stop 22 which prevents displacement of the rod when moved upward. The rod 20 functions as an agita-
15 tor to prevent choking of the pipe 14 or the outlet opening 15 so that a flow of the oil is assured.

What is claimed is:

An oil purifier comprising a receptacle, a
20 heating coil within and spanning said re-
ceptacle, a removable funnel having its

flared part adapted to rest on the upper edge of said receptacle, a pipe depending from the funnel and through the coil with the discharge end thereof below the coil, a 25 screen within the funnel, an agitator rod passing through said funnel and having a stop at the lower end thereof below the pipe, a cover for the funnel through which said rod passes, a screen within the receptacle 30 and supported by said coil, outlet means from the receptacle above the second mentioned screen, whereby as the oil level rises the oil will pass through the second mentioned screen and then to said outlet means.
35

In testimony whereof I affix my signature in presence of two witnesses.

HENRY W. ROSE.
